GOBLET OR THE LIKE

Lawrence V. Block, Sapulpa, Okla., assignor to Bartlett-Collins Company, Sapulpa, Okla., a corporation of Delaware

Application May 16, 1955, Serial No. 36,021

Term of patent 14 years

(Cl. D36—8)

Fig. 1

Fig. 4

Fig. 3

Fig. 2

Figure 1 is a side view in elevation of a goblet or the like, showing my new design;

Figures 2, 3 and 4 are horizontal sections, respectively, taken along the lines II—II, III—III, and IV—IV of Figure 1; and

I claim:

The ornamental design for a goblet or the like, as shown.
